UNITED STATES PATENT OFFICE.

CHARLES BLUE WRIGHT, OF JERSEY CITY, NEW JERSEY, ASSIGNOR OF ONE-HALF
TO EDWARD G. NELSON, OF NEW YORK, N. Y.

COMPOSING-STICK.

1,381,888.

Specification of Letters Patent. Patented June 14, 1921.

Application filed August 16, 1920. Serial No. 403,699.

To all whom it may concern:

Be it known that I, CHARLES BLUE WRIGHT, a citizen of the United States, and a resident of Jersey City, in the county of 5 Hudson and State of New Jersey, have invented a new and Improved Composing-Stick, of which the following is a full, clear, and exact description.

The invention relates to printing and its 10 object is to provide a new and improved composing stick arranged to enable the user to open the filled stick for removal of the set-up type or any part thereof.

Another object is to enable the compositor 15 to correctly set the type in case a stereotype or other insert is to be used in conjunction with the said type and without requiring such stereotype for the insert on the stick.

20 With these and other objects in view the invention consists of certain novel features of construction as hereinafter shown and described and then specifically pointed out in the claims.

25 A practical embodiment of the invention is represented in the accompanying drawings forming a part of this specification in which similar characters of reference indicate corresponding parts in all the views.

30 Figure 1 is a plan view of the composing stick.

Fig. 2 is a sectional side elevation of the same on the line 2—2 of Fig. 1.

Fig. 3 is a perspective view of the knee; 35 and

Fig. 4 is a similar view of the setting member.

The composing stick in its general construction comprises a body 10, a side wall 11, an end wall 12, a knee 13 and a setting member 14, the knee and setting member being slidable on the side wall 11 to permit of adjusting the knee relative to the end wall 12 according to the height of the column 40 of type to be set. The body 10 is preferably made of glass or other diaphanous material and its upper face is roughened or frosted to permit of conveniently tracing thereon with a lead pencil, chalk, or other 45 means, at any desired portion the outline of an electrotype or other insert around which the type is to be grouped. The side wall 11, the end wall 12, the knee 13 and its setting member 14 are preferably made of 50 metal and the said side wall 11 and the end

wall 12 are secured to the body 10 by screws or other suitable fastening devices 21.

The knee 13 extends across the body 10 and is provided at its right hand end with spaced lugs 25, 26 having at their under sides registering grooves or guide-ways 27 slidingly engaging the side wall 11. The setting member 14 extends between the lugs 25 and 26 and is provided on its under side with a groove or a guideway 30 slidingly 60 engaging the side wall 11. A set screw 31 screws in the outer side of the setting member 14 and abuts against the side wall 11 to fasten the setting member 14 in position after the knee 13 and the setting member 14 are set to the desired position. The lugs 25 and 26 are spaced apart a distance in excess to the length of the setting member 14 to allow the compositor to move the knee 13 a short distance rearward on the side wall 75 11 independent of the setting member 14. Normally the knee 13 is in forward position as shown in Fig. 1 and is locked therein by a locking bolt 40 adapted to engage an opening 41 formed in the setting member 14. (See Fig. 2.) The bolt 40 is mounted to slide in a bore 42 formed side-wise in the knee 13, and the bolt 40 is provided with a reduced portion 43 terminating in a knob 44 adapted to be taken hold 80 of by the compositor for moving the bolt 40 out of locking position relative to the opening 41 in the setting member 14. The bolt 40 is pressed on by a spring 45 coiled around the reduced portion 43 and extending within the bore 42. By the arrangement described the spring 45 normally holds the bolt 40 in engagement with the opening 41 at a time the lug 25 of the knee 13 is spaced from the forward end of the setting member 14.

In using the composing stick the compositor loosens the set screw 31 and moves the setting member 14 and the knee 13 forward or rearward on the side wall 11 until the distance between the end wall 12 and the knee 13 corresponds to the height of the column of type to be set at a time. When this has been done the compositor screws up the set screw 31 to fasten the setting member 14 100 and the knee 13 in the adjusted position, it being understood that the knee 13 moves with the setting member 14 owing to the bolt 40 engaging the opening 41. The compositor now fills the composing stick in the usual 105 110

manner with the type and by having the outline 20 of an electrotype or other insert marked on the body 10 the compositor is enabled to readily set the type around such outline, thus providing an opening for the electrotype or other insert. After the composing stick has been filled the compositor moves the knob 44 to the left, thus withdrawing the bolt 40 from the opening 41, thereby unlocking the knee 13 from the setting member 14 and allowing the compositor to slide the knee 13 rearwardly until its lug 25 abuts against the forward end of the setting member 14. The type is now unlocked 15 and can be readily removed from the composing stick. When this has been done the compositor simply pushes the knee 13 forward until the bolt 40 snaps into the opening 41, thus again locking the knee 13 to the setting member 14. The composing stick can now again be filled with another set of type. The composing stick shown and described is very simple, durable in construction, and composed of comparatively few 20 parts not liable to get out of order easily. 25

I claim:

1. A composing stick having a diaphanous body, and means thereon to permit of tracing the outline of an insert on the said body.
2. A composing stick having a diaphanous body provided with a roughened surface to permit of tracing thereon the outline of an insert.
3. A composing stick comprising a body having a fixed end wall, a fixed side wall and a knee slideable on the side wall, and a setting member slideable on the side wall and adapted to be fastened thereto, the said knee having a limited sliding movement relative

to the said setting member to allow of opening 40 the stick without disturbing the set thereof.

4. A composing stick comprising a body having a fixed end wall, a fixed side wall and knee slideable on the side wall, and a setting 45 member slideable on the side wall and adapted to be fastened thereto, the said knee having a limited sliding movement relative to the said setting member to allow of opening the stick without disturbing the set thereof, and 50 a locking means adapted to lock the knee to the setting member when in set position and to allow of unlocking and opening the knee relative to the setting member.

5. A composing stick comprising a body 55 having a fixed end wall, a fixed side wall and a knee, the knee having spaced lugs slidably engaging the said side wall, a setting member slidably engaging the said side wall and extending between the said lugs to permit a limited 60 sliding movement of the knee relative to the setting member, a set screw fastening the setting member to the said side wall and a spring pressed locking pin slideable on the knee and adapted to engage the said setting 65 member to lock the knee in place on the setting member.

6. A composing stick comprising a body, a knee and a setting member for the knee, the knee and setting member being slideable 70 on the said body and the knee having a limited sliding movement relative to the setting member, a set screw fastening the setting member to the said body, and a spring pressed locking bolt adapted to lock the knee 75 to the setting member.

CHARLES BLUE WRIGHT.
